Attorney

UNITED STATES PATENT OFFICE.

FERDINAND A. BUESCHER, OF ELKHART, INDIANA.

KEY PAD FOR WIND MUSICAL INSTRUMENTS.

Application filed December 9, 1924. Serial No. 754,810.

This invention relates to key pads for wind musical instruments and proposes the construction of a pad of the glued-in type having means for restraining the tendency 5 of the pad to bulge at the center when damped by the moisture of respiration, an inherent fault of glued-in pads as heretofore constructed, and which spoils the tone of the instrument by causing the central portion 10 of the pad to extend into and partially obstruct the valve opening with which the pad is associated.

Another object of the invention is to provide means for condensing the felt or other 15 yielding material of the pad in the peripheral portions thereof so as to improve its seating qualities.

Other objects of the invention will presently appear.

20 In my Patent No. 1,401,872, granted Dec. 27, 1921, is disclosed a replaceable pad in which glue is not used, the pad being secured to the key in a quickly attachable or detachable manner by means such as a snap fastening. Incidentally another advantage is found in the construction disclosed in said patent in that the snap fastening includes a headed element extending through an aperture in the pad, with the headed portion 25 thereof compressing the central part of the pad and thereby preventing its bulging. Chiefly through innate conservatism a great many musicians still prefer to use a pad of the glued-in type, and the present invention 30 is promulgated with a view to giving them the advantages accruing from the use of a centrally positioned bulge-restraining member while relieving them of the need of using a pad of the quick replaceable type.

40 In the drawings:-

Figure 1 is a plan view of the key of a wind musical instrument furnished with a pad embodying the principles of the present invention.

45 Figure 2 is a cross section through the key tampion, pad and the opening with which it is associated, the parts being shown in open relation.

Figure 3 is a similar view with the parts 50 in closed relation.

Figures 4 and 5 are sectional views showing open and closed positions of an old style glued-in pad indicating the objectionable bulge acquired through absorption of 55 moisture by the pad.

Referring now in detail to the several fig-

ures, the numeral 1 represents the key tampon which in the present illustrative embodiment happens to be that of a saxophone and therefore cup shaped, as is usual. The 60 pad consists of a yielding compressible disk 2 or felt or other suitable material backed by a substantially rigid plate 3, preferably metallic and covered with a facing 4 of kid skin or the like and which is turned over the 65 peripheral edge of the plate 3 and drawn taut by a thread 5 stitched around the peripheral edge of the kid skin.

There is nothing unusual or novel in the 70 construction in so far as it has been described, but for the purpose of restraining the tendency to bulge of the middle portion of the pad, said pad, including the kid skin, disk, and plate 3, is perforated, and a securing member 6, formed of a head and a 75 shank, which may be a rivet, is introduced through said perforation, and with the head of the member 6 bearing compressively against the central portion of the outer face of the disk 2 whereby when the member 6 80 is secured in position the central portion of the pad will be tightly compressed to provide for it being permanently of less thickness than the remaining portion of the pad. The head of the member 6 is of appropriate 85 thinness, of materially greater diameter than the diameter of the shank, of segmental contour in cross section and has its inner face flat throughout. The inner end of the shank of the member 6 which protrudes beyond the plate 3 may be secured in any suitable manner as by riveting or turning it over against said plate. Not only does the duplex headed member prevent bulging of the 90 pad in the middle but it presses out the 95 yielding material of the pad into the peripheral portions thereof compressing it and improving its seating quality. The pad is applied to the key tampion in the usual manner, by placing a little glue along the 100 annular portion of the kid skin which overlaps the plate 3 and then pressing the pad into place within the tampion.

While I have here shown what I believe to be a simple and efficient form of the 105 invention it is to be understood that numerous alterations in the details of construction such as may be developed through the exigencies of use may be resorted to without transcending the scope of the invention as 110 defined by the appended claims.

Having described my invention what I

claim as new and desire to secure by Letters Patent, is:—

1. In a key-pad for wind musical instruments, a tampion, a compressible pad therefor secured thereto, and a pad compressing element including a shank extending centrally through and snugly engaged throughout by the body of the pad to prevent the shifting of the latter relative to the shank, said shank having its ends provided with means clamping against the inner and outer faces of the pad to maintain the central portion of the latter under a permanent state of compression and to prevent the central portion of the outer face of the pad from bulging with respect to the remaining portion of said outer face.
2. In a key-pad for wind musical instruments, a tampion, a compressible pad therefor secured thereto, and a pad compressing element including a shank extending centrally through said pad and having its ends provided with means clamping against the inner and outer faces of the pad to maintain the central portion of the latter under a permanent state of compression and to prevent the central portion of the outer face of the pad from bulging with respect to the remaining portion of said outer face, said means at the ends of the shank being in the form of heads, the head at the outer end of the shank being of appropriate thinness, of segmental contour in cross section and having a flat inner face.
3. In a key-pad for wind musical instruments, a tampion, a compressible pad there-

for secured thereto, and a pad compressing element including a shank extending centrally through said pad and having its ends provided with means clamping against the inner and outer faces of the pad to maintain the central portion of the latter under a permanent state of compression and to prevent the central portion of the outer face of the pad from bulging with respect to the remaining portion of said outer face, said means at the ends of the shank being in the form of heads, the head at the outer end of the shank of greater diameter than the head at the inner end of the shank, said head at the outer end of the shank positioned inwardly and outwardly with respect to that portion of the outer face of the pad free of contact with the inner face of such head.

4. In a key-pad for wind musical instruments, a tampion, a compressible pad therefor secured thereto, and a pad compressing element including a shank extending centrally through said pad and having its ends provided with means clamping against the inner and outer faces of the pad to maintain the central portion of the latter under a permanent state of compression and to prevent the central portion of the outer face of the pad from bulging with respect to the remaining portion of said outer face, the clamping means at the outer end of the shank being of greater area than the clamping means at the inner end of the shank.

In testimony whereof I have hereunto set my hand.

FERDINAND A. BUESCHER.
